UNITED STATES PATENT OFFICE

ALFRED F. HORN, OF CHARLEROI, PENNSYLVANIA, ASSIGNOR TO MACBETH-EVANS
GLASS COMPANY, OF CHARLEROI, PENNSYLVANIA, A CORPORATION OF PENNSYLVANIA

DESIGN FOR A SHADE OR REFLECTOR

Application filed August 14, 1931. Serial No. 40,854. Term of patent 3½ years.

To all whom it may concern:

Be it known that I, ALFRED F. HORN, a citizen of the United States of America, and a resident of Charleroi, county of Washington, Commonwealth of Pennsylvania, have invented a new, original, and ornamental Design for a Shade or Reflector, of which the following is a specification, reference being had to the accompanying drawings, forming a part hereof.

In the drawings an unfinished portion of each of the figures is shown intended to indicate a repeat of the finished portion.

The shade or reflector may be used pendant or upright, as desired.

I claim:

The ornamental design for a shade or reflector, substantially as shown and described.

ALFRED F. HORN.
